UNITED STATES PATENT OFFICE

ALFRED C. DANKS, OF CLEVELAND, OHIO, AND KINGSLEY L. MARTIN, OF MONTCLAIR, NEW JERSEY

WATER-TUBE BOILER

Application filed October 2, 1928. Serial No. 309,764.

The invention relates to water tube boiler constructions, and particularly to baffle walls, as used in boilers of a wide variety of types, such as, Sterling, Connelly, Heine and others, in which the tubes are upright in general direction and parallel or approximately so. The invention has for its primary objects; the provision of a baffle wall, whose construction involves a saving of time and labor; the provision of a composite wall partially of plastic refractory material hardened in place, which is more resistant to heat and more durable than the baffle walls heretofore used composed entirely of plastic refractory material hardened in place; and the provision of a baffle wall, whose body portion is of plastic refractory composition hardened in place, which may be constructed without the wood forms heretofore ordinarily used. One embodiment of the invention is illustrated in the accompanying drawings, wherein:

Figure 1 is a vertical section through one type of water tube boiler employing the improved baffle wall. Fig. 2 is a fragmentary front elevation showing a small portion of the baffle wall. Fig. 3 is a section on the line III—III of Fig. 2. And Fig. 4 is a section similar to that of Fig. 3 through a modified form of the invention.

Referring to the drawings, 1 is the lower drum of a water tube boiler, 2 is the upper drum, and 3, 4 and 5 are the front, middle and rear banks of tubes respectively. In the particular construction shown, which is merely one of a large number in which the improved baffle may be used, the boiler is fired by suitable gas burners directed through the openings 6 and 7, but any form of firing may be used. The front baffle is made up of the parts 8 and 9, and the rear baffle of the parts 10 and 11, the gases of combustion following the path indicated by the arrows and discharging through the flue 12. The parts 8 and 10 of the baffles, which constitute the novel subject matter, are constructed in ac-

cordance with the showing in Figs. 2 and 3, while the sections 9 and 11 are of ordinary construction, each consisting of a layer of originally plastic material hardened in place, such compositions being well known in the art.

As shown in Figs. 2 and 3, the wall 8 consists of strips or blocks 13, 13, 13, etc. of premolded refractory material, such as, brick or tile, of any desired length and just wide enough to bridge the spaces between the tubes, the edges of the strips being preferably beveled, as shown, in order to fit the curve of the tubes. Between the sets of strips as thus provided is a filler or body portion 14 of the so-called plastic refractory material heretofore referred to.

In fabricating a wall, such as the wall 8, the strips or blocks 13, 13, 13 on one side of the space between the tubes to be filled, are first all put in position followed by the bottom row of opposing strips, and the space thus provided is filled with the plastic material 14. The next row of strips is then positioned on the first row and more plastic added. This is continued until the wall 8 is completed.

The premolded strips or blocks 13, 13, 13, etc. are much more resistant to heat than the plastic material 14, so that the composite wall will stand up under severe heat conditions better than a wall composed entirely of the plastic material. The composite wall is thus particularly serviceable in a wall located as is the wall 8, which receives the radiant heat directly from the coal and gas fires in the combustion space 15. The premolded blocks are also harder than the plastic material and will stand the attrition from dust better. Where wood forms are used in constructing a wall, which is all plastic material, such forms are difficult of removal, and if left to be burned out sometimes conceal cracks and voids in the plastic material which must then be patched or repaired involving additional expense and labor. The use of the tile or brick blocks

avoids this difficulty, as the refractory facing as thus provided compensates for any cracks or defects existing in the plastic filler.

The invention also contemplates a modification of the wall, as just described, such modification being illustrated in Fig. 4. As here shown, the brick or tile blocks or strips 13, 13, 13 are placed on one side only of the layer of plastic material 14. This construction, although not as desirable as that of Fig. 2, may be used to advantage under certain conditions, the strips 13, 13, 13, etc. being placed on the side of the wall which is exposed to the greatest heat. Wood forms may be used to hold the plastic material on the side opposite to the strips 13, such forms being either removed after the plastic has set or else left in the furnace and burned out.

What we claim is:

- 20 1. In combination in a water tube boiler having rows of upwardly extending substantially parallel tubes, a baffle wall lying between adjacent rows of tubes and comprising a series of plates of molded refractory material extending longitudinally of the tubes of one row bridging the space between such tubes and of greater width than the clearance between the tubes, and a layer of originally plastic material hardened in position against said plates between such plates and the row of tubes nearest the surface formed by the aforesaid tubes and plates.
- 25 2. In combination in a water tube boiler having rows of upwardly extending substantially parallel tubes, a baffle wall lying between adjacent rows of tubes and comprising a series of plates of molded refractory material extending longitudinally of the tubes of one row bridging the space between such tubes and of greater width than the clearance between the tubes, and a layer of originally plastic material hardened in position against said plates between such plates and the row of tubes nearest the surface formed by the aforesaid tubes and plates, said plates having their side edges which engage the tubes beveled.
- 30 3. In combination in a water tube boiler having rows of upwardly extending substantially parallel tubes, a baffle wall lying between two adjacent rows of tubes and comprising a set of plates of molded refractory material extending longitudinally of the tubes of each row bridging the spaces between such tubes and of greater width than the clearance between the tubes, and a filler of originally plastic material hardened in position between the two sets of plates and the two rows of tubes.
- 35 4. In combination in a water tube boiler having rows of upwardly extending substantially parallel tubes, a baffle wall lying between two adjacent rows of tubes and comprising a set of plates of molded refractory material extending longitudinally of the

tubes of each row bridging the spaces between such tubes and of greater width than the clearance between the tubes, and a filler of originally plastic material hardened in position between the two sets of plates and the two rows of tubes, said plates having their side edges which engage the tubes beveled.

In testimony whereof, we have hereunto subscribed our names.

ALFRED C. DANKS.
KINGSLEY L. MARTIN.
